US0D1102564S

(12) **United States Design Patent** (10) Patent No.: **US D1,102,564 S**
(45) Date of Patent: ** *Nov. 18, 2025

(54) **BRANCHED PIPE FOR FLUID DISTRIBUTION**

(71) Applicant: **INDUSTRIAL FLOW SOLUTIONS OPERATING LLC**, New Haven, CT (US)

(72) Inventor: **Stephane Dumonceaux**, Burcy (FR)

(73) Assignee: **Industrial Flow Solutions Operating, LLC**, New Haven, CT (US)

(*) Notice: This patent is subject to a terminal disclaimer.

(**) Term: **15 Years**

(21) Appl. No.: **29/875,033**

(22) Filed: **Apr. 27, 2023**

(57) **CLAIM**

The ornamental design for a branched pipe for fluid distribution, as shown and described.

DESCRIPTION

FIG. 1 is a front, top, right side perspective view of a branched pipe for fluid distribution, in accordance with the present invention;

FIG. 2 is a rear, bottom, left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines represent portions of the branched pipe for fluid distribution that form no part of the claimed design.

1 Claim, 8 Drawing Sheets
